[57] CLAIM

The ornamental design for a chopstick holder, as shown and described.

DESCRIPTION

FIG. 1 is a perspective view of a chopstick holder showing my new design,
FIG. 2 is a front elevational view thereof,
FIG. 3 is a top view thereof,
FIG. 4 is a right side elevational view thereof with the article rotated 90° from the position shown in FIG. 1,
FIG. 5 is a sectional view thereof as seen along the line 5—5 in FIG. 3,
FIG. 6 is a rear sectional view thereof, and
FIG. 7 is a sectional view thereof as seen along the line 7—7 in FIG. 2.
The bottom and left side elevational views are substantially the same as the top view and right side view, respectively.

FIG. 1**FIG. 2****FIG. 5****FIG. 3****FIG. 4****FIG. 6****FIG. 7**
